Inventor,

George Colvin Kennedy.

UNITED STATES PATENT OFFICE.

GEORGE COLVIN KENNEDY, OF WATERLOO, IOWA.

FORCE-DELIVERY SYRINGE.

1,308,954.

Specification of Letters Patent. Patented July 8, 1919.

Application filed January 16, 1918. Serial No. 212,037.

To all whom it may concern:

Be it known that I, GEORGE COLVIN KENNEDY, a citizen of the United States of America, and a resident of Waterloo, Black Hawk county, Iowa, have invented certain new and useful Improvements in Force-Delivery Syringes, of which the following is a specification.

My invention relates to improvements in force-delivery syringes, and the object of my improvement is to provide means for successfully operating the mechanism of the syringe from a distance.

This object I have accomplished by the means which are hereinafter described and claimed, and which are illustrated in the accompanying drawings, in which:

Figure 1 is a vertical central longitudinal section of the vessel and its supporting-means of my improved force-delivery syringe, parts being broken away; Fig. 2 is an upper plan view of the same; Fig. 3 is a front elevation of the supporting-means for said vessel and of the traction-means, and Fig. 4 is a perspective view of the guide-brackets.

Similar numerals of reference denote corresponding parts throughout the several views.

30 The numeral 1 denotes a hollow cylindrical vessel, having an open upper end, and a closed lower end of conical form 3 terminating in an orificed nipple 4 upon which one end of a flexible tube 30 is mounted, the 35 other end of said tube being supplied with a detachable delivery-nipple 31.

The upper end of said vessel is thickened at 2 to provide an annular ledge or fillet. The numeral 5 denotes a back-plate having 40 at its upper end a hanging orifice 6, and also having a plurality of holes 7 to receive nails or screws whereby the plate may be fixed to a wall or other supporting structure. The numeral 8 denotes a ring or sleeve 45 which is riveted or spot-welded to said plate 5 to extend horizontally therefrom, and the vessel is mounted in said ring with its fillet 2 seated on the upper edge thereof, removably.

Opposite to the plate 5 a bracket 9 is 50 riveted or spot-welded or otherwise fixedly mounted on said ring, and has its upper and lower parts bent in the same direction horizontally forward, to provide flat arms 10 and 14 which have vertically alined orifices 55 11 and 15 and other vertically alined smaller orifices 12 and 16, and the extremity of the

upper arm 10 has a bifurcation 13, the forks having approximated tips as shown. When not in use the nipple 31 may be lifted, and the tube 30 thereunder compressed and 60 mounted in the said bifurcation, whereby the nipple is held above the level of any liquid in said vessel.

The numeral 21 denotes a piston mounted to move through said vessel 1, and is provided with a circumferential groove to detachably receive an inner annular rib on an elastic packing-ring 22 to hold the ring on the piston securely and prevent leakage between it and the inner wall of the vessel. 65 Said ring 22 preferably has a depending lower edge, which may be coned as shown, whereby the liquid confined under pressure of the descending piston will exert pressure against the depending edge to seal the same 70 to the vessel wall to aid in preventing leakage. The piston has a central socketed boss 26 to detachably receive the lower end of a piston-rod 27, the latter having a transverse orifice 25 alined with transverse orifices 75 24 in said boss, said orifices receiving a split-key 23 removably.

The upper part of said piston-rod 27 is bent laterally horizontally past the vessel then bent downwardly vertically to depend 80 adjacent to the forward wall of the vessel through the orifices 11 and 15 of the guide-arms 10 and 14 slidably.

The numeral 28 denotes a ring fixed on the depending or reversely-bent part of said 85 piston-rod above the arm 10, and has a hook to receive a loop made in the upper end of a flexible traction-cord 20, the latter depending through the orifices 12 and 16 in the arms 10 and 14, and having its other end 90 secured to the nipple 31. In Fig. 4 is shown a modification, in which a small pulley-block 18 is swingingly mounted on the lower arm 14 by means of a link 17 inserted in the orifice 16, and the cord 20 is passed about the 95 sheave in said block, whereby the sheave acts as anti-friction bearing means for the cord, and which permits traction to be applied from a distance to the cord, and from a horizontal or other direction, to operate the 100 piston in forcing it downwardly without difficulty.

It will be perceived that when the piston-rod is pushed down the reversely-bent part will slide in the orifice in said guide-arms 110 without binding, and will guide the piston 21 in its movements to prevent the latter

tilting or binding in said vessel, thus preventing any leakage or difficulty in its operation.

The user can actuate the device from a distance, by means of the traction-cord 20, which renders the same useful in hospitals or in other places, and especially in locations where the syringe must be mounted at a low level where a gravity-delivery would not be possible, and traction may be varied at will to propel liquid from the delivery-nipple 31 with a desired force.

Having described my invention, what I claim as new, and desire to secure by Letters Patent, is:

1. In a device of the character described, a vessel provided with a delivery port, a piston in said vessel, supporting-means in which said vessel is removably mounted, said 20 supporting-means including a guideway, and a piston-rod connected to said piston, extending without the vessel, having its outward part reversely bent and slidably mounted in said guideway.
2. In a device of the character described, a vessel having a delivery-orifice, a piston in said vessel, a piston-rod on said piston having its upper part projected from the vessel and bent to one side, supporting- 30 means in which said vessel is removably mounted, a guideway on said supporting-means in which the bent part of said piston-rod is slidably mounted, and traction-means

connected to said piston-rod for moving it downwardly operable from a distance. 35

3. In a device of the character described, a vessel having its lower end closed and provided with an outlet-port, a piston movable in said vessel, a piston-rod detachably connected to said piston, projected through the 40 upper end of the vessel and bent over to one side, supporting-means for said vessel, guides on said supporting-means for the bent-over part of said piston-rod, said guides having an orifice, and a traction-cord 45 connected to said piston-rod above said guides and passed down through the orifice therein.

4. In a device of the character described, a vessel having its lower end provided with a delivery-port, a piston in said vessel, a piston-rod on said piston having its upper part bent reversely over to extend downwardly at one side of the vessel, a guideway having alined orifices to receive the bent-over part of said piston-rod slidingly, a pulley swingingly mounted on said guideway, a traction-cord connected to said piston-rod above said pulley and passed downwardly about the sheave in the pulley, a flexible tube in communication with the delivery-port of said vessel, and said traction-cord having its other end connected to said flexible tube. 55

Signed at Waterloo, Iowa, this 12th day of January, 1918.

GEORGE COLVIN KENNEDY.
